United States Patent Office

Des. 196,733
Patented Oct. 29, 1963

196,733

DESK

Alfred Huller, New York, N.Y., and Reginald Squire, Lime, Conn., assignors to Huller, Inc., New York, N.Y., a corporation

Filed Mar. 30, 1962, Ser. No. 69,505

Term of patent 14 years

(Cl. D33—7)

FIG. 1

FIG. 2

FIG. 3

FIG. 4

FIG. 5

FIG. 6

FIG. 1 is a perspective view of a desk showing our new design;

FIG. 2 is a horizontal sectional view taken on the line 2-2 of FIG. 1;

FIG. 3 is an enlarged vertical sectional view taken on the line 3-3 of FIG. 1;

FIG. 4 is a front elevational view;

FIG. 5 is a side elevational view; and

FIG. 6 is a sectional view taken through line 6-6 of FIG. 1.

We claim:

The ornamental design for a desk, substantially as shown.
